(57) **CLAIM**

The ornamental design for pew and bench with pivoting seat, as shown and described in the drawings.

DESCRIPTION

FIG. 1 is a front perspective view of a pew and bench with pivoting seat in accordance with the new design;

FIG. 2 is a front elevational view thereof;

FIG. 3 is a top plan view thereof;

FIG. 4 is a rear elevational view thereof;

FIG. 5 is a left side elevational view thereof;

FIG. 6 is a right side elevational view thereof;

FIG. 7 is a front perspective view of another pew and bench with pivoting seat in accordance with the new design;

FIG. 8 is a front elevational view thereof;

FIG. 9 is a top plan view thereof;

FIG. 10 is a rear elevational view thereof;

FIG. 11 is a left side elevational view thereof; and,

FIG. 12 is a right side elevational view thereof.

The broken lines shown in the drawings are for illustrative purposes only and form no part of the claimed design.
